(57) **CLAIM**

The ornamental design for a bicycle hanger as shown and described.

DESCRIPTION

FIG. 1 is a perspective view of a bicycle hanger showing my new design;

FIG. 2 is a front view thereof;

FIG. 3 is an enlarged right view thereof;

FIG. 4 is an enlarged left view thereof;

FIG. 5 is a back view thereof;

FIG. 6 is a bottom view thereof;

FIG. 7 is a top view thereof;

FIG. 8 is an enlarged view of the encircled area 8 of FIG. 1;

FIG. 9 is an enlarged view of the encircled area 9 of FIG. 2; FIG. 10 is an enlarged view of the encircled area 10 of FIG. 3;

FIG. 11 is an enlarged view of the encircled area 11 of FIG. 5;

FIG. 12 is an enlarged view of the encircled area 12 of FIG. 6; and,

FIG. 13 is an enlarged view of the encircled area 13 of FIG. 7.

The broken lines shown on the drawings depict portions of the bicycle hanger that form no part of the claimed design.
